UNITED STATES PATENT OFFICE.

RALPH BAGGALY, OF PITTSBURG, PENNSYLVANIA.

CONVERTING COPPER MATTE.

SPECIFICATION forming part of Letters Patent No. 746,249, dated December 8, 1903.

Application filed April 7, 1903. Serial No. 151,529. (No specimens.)

To all whom it may concern:

Be it known that I, RALPH BAGGALY, of Pittsburgh, Allegheny county, Pennsylvania, have invented a new and useful Method of 5 Converting Copper Matte, of which the following is a full, clear, and exact description, reference being had to the accompanying drawings, forming part of this specification, in which—

10 Figure 1 is a side elevation of the converter, partly in longitudinal section. Figs. 2 and 3 are elevations of the opposite ends, respectively. Fig. 4 is a vertical cross-section on the line IV IV of Fig. 1.

15 It is well known that the heat in the early stages of converting is increased and decreased by the volume of the blast alone, and can thus be readily controlled. In the present practice, however, the heat of converting 20 must be kept comparatively low, because the converter as at present used will be quickly destroyed by higher heats. For this reason the blast is delivered to the converter in moderate volume, and the converting process 25 is therefore continued sometimes for more than three hours simply because the converter-walls will not admit of higher temperatures being used. In addition to this, in the present converters it is impossible to use brick 30 linings, notwithstanding the fact that such linings would be much cheaper than others, because of the fact that it has been found that the heat of the interior walls will rapidly penetrate any kind of brick and will weaken 35 and destroy the metal shell of the converter itself.

The refining of copper by my process consists simply in the elimination of various elements successively in the order in which each 40 can be oxidized.

The atmosphere furnishes the cheapest source of supply of oxygen, and the reason that copper, gold, silver, nickel, and cobalt are freed from their impurities through the 45 action of the converting-blast is because iron, arsenic, selenium, tellurium, bismuth, antimony, lead, and other elements are oxidized, and thus eliminated, before oxidizing commences in the case of the above-mentioned 50 metals, which it is desired to recover. Hence the larger the volume of air that is delivered

into the molten mass the greater the resulting heat and the quicker the desired result is accomplished.

In my process I use a greater volume of 55 blast, preferably two, three, or even five times the volume of blast, in a given time than is used in present practice, and I accomplish a given amount of work for this reason in a fraction of the time at present required. 60

Should converters as at present used be provided with water-jackets or even with coils for the circulation of water or air through the lining at the latter portion of the converting process when the heat begins to fail 65 through the reduced percentages of oxidizable impurities, or when the matte has reached approximately seventy per cent. or eighty per cent. of copper, the contents of the converter will solidify and the process will be brought 70 to a standstill and the desired refining rendered abortive. In the ordinary converter not provided with water-jackets, even with the addition of blocks of cord-wood from time to time in a feeble effort to maintain the temperature until the process can be rushed 75 through to completion, great difficulty is experienced and great expense is incurred.

Sometimes the refining process is brought 80 to a standstill through the obstruction of the blast by the formation of "copper noses" on the ends of the twyers in the converter. The final operation is thus rendered erratic and uncertain and is at times unduly hastened in order to complete the work before the mass 85 solidifies. The net result of these conditions is necessarily poor work, or at all events not such good and perfect work as would be possible where the temperature of the molten mass can be regulated at will and held just 90 high enough so that it would be impossible for copper noses to form.

I provide for and counteract the injurious effects that would otherwise result from the greatly-increased volume of blast with its consequent increased heats in the early stages of the converting process by means of abundant streams of cooling water flowing through a number of narrow metal jackets, which cooling streams are capable of regulation at will 95 in each separate jacket, while during the later stages of the converting process I supply to 100

the converter the auxiliary heat of a flame that is also capable of regulation at will and by means of which I am enabled to produce the best work and with the greatest economy, 5 dispensing entirely with the present tedious, expensive, and unworkmanlike practice of removing copper noses by steel bars, sledgehammers, and manual labor.

Fluxes of any kind, whether they be silica, 10 iron, lime, dolomite, or other flux, will be quickly melted through the intense heat and violent agitation of the molten mass produced by the great volume of air and will be quickly mixed and readily taken up by the mass as a 15 means of forming the desired slag.

In the accompanying drawings I show a converter suitable for the practice of my invention.

22 are metal end plates of the converter, 20 which are preferably dished and are connected by longitudinal bars or channels 3, which constitute therewith a supporting-cradle for the water-jackets and the contained refractory lining. These water-jackets are made 25 of parallel sections 4 4, which are shaped to suit the contour of the converter and are preferably long and narrow. They are set edge to edge, being connected by bolts passing through marginal flanges 5, and they are provided with transverse flanges 6, which fit 30 against the sides of one of the channel-bars, as shown in Fig. 4, and are secured thereto and to each other by bolts 7. The water-jackets at the ends of the converter are constituted by hollow plates 8 8', set on the inner side of the end plates 22.

Each of the jacket-sections 4 4 and each of the sections 8 8' has a water-inlet 9, communicating with a water-supply pipe 10, which 40 derives its water from a swiveled water connection 11 at the axis of rotation at one end of the converter, and at the upper end each of the sections has an outlet-passage 12, connecting with a pipe 13, leading to a vertical flexible stand-pipe 14, which being elevated insures that the water-jackets are always kept 45 full of water and that escape of bubbles of steam and air can freely occur. Being flexible the stand-pipe does not interfere with the 50 rotation of the converter.

Inside the water-jackets is a refractory lining 15, made of bricks composed of chrome ore, magnesite, silica, or dolomite, or the lining may be made of plastic refractory material rammed in place. I prefer, however, to 55 make the lining of bricks. This has not hitherto been done in copper-converters, and I am enabled to do it by the use of the water-jackets, which keep the outer surface of the 60 converter from becoming overheated.

The upper part of the converter is constituted by a removable section 16, composed of a metal shell 17 with an interior refractory lining, and it is provided with suitable lifting rings or lugs 18, by which when desired 65 it can be removed to afford access to the interior for purposes of repair.

The converter has twyers 19, extending through the refractory lining and through the water-jackets to a wind-box 20, which derives its supply of air from a pipe 21, swiveled at the end of the converter in the axis of rotation. 70

The converter is preferably mounted on wheels 22, which are journaled in a foundation 23, the end plates 22 being formed with a peripheral rim 24, which bears on the wheels. The wheels 22 at one end of the converter are provided with flanges which engage and hold the rim 24; but the wheels 22 80 at the other end are unflanged, so as to permit free longitudinal expansion of the converter.

In order to rotate the converter, I provide it at one end with a segmental pinion 25, engaging a rack 26, which may be reciprocated by a power-cylinder 27 or other suitable means. This rack may be held in engagement with the pinion by a cam 28, which bears against the back of the rack and constitutes 90 a guide. By rotating the cam the rack is freed and can be disengaged from the pinion.

S is a spout by which fluxes can be delivered to the converter, Fig. 4.

The converter is provided with means for supplying the heat of a flame to the surface of the charge at the end of the blow when nearly all the bases of the matte have been oxidized, and the heat of oxidation has thus failed. For this purpose I introduce at the 95 end of the converter one or more burners 29, adapted to supply a jet of gas or of oil sprayed with air or steam, and I am enabled thereby to generate in the converter as intense degree of heat as may be required. The pipes 105 30 and 31, which supply the burner, are provided with swinging joints, so that they will not interfere with the rotation of the converter. In using the converter it is charged with molten matte, and jets of air are blown 110 into it from the twyers, the air being supplied in large volume, as above stated. This effects the conversion much more rapidly than at present, and I am enabled to do this by the use of the water-jackets back of the refractory lining, which prevent the destruction 115 of the converter-shell at the beginning of the blow, when the oxidation and generation of the heat are rapid, and by the use of the burner 29, from which I supply heat to the 120 surface of the charge toward the end of the blow, when the oxidation and heat of chemical combination fail. By the auxiliary heat of the burner I can retain the matte during the final stage of the blow in the necessary hot and liquid condition without danger of chilling it by the water in the jackets or by the cooling effect 125 of the large blast of air. The heat from the burner also prevents the formation of copper noses at the twyers, which heretofore have constituted a source of annoyance and expense.

It will thus be seen that by the cooling action 130 of the water I prevent the destruction of the converter by the high temperature generated

at the early stages of the blow by the large volume of air which I employ, and that by the auxiliary heat of the flame above the charge I prevent the tendency to freezing of the metal, which, owing to the presence of the water-jacket and the air-blast, would be greater than in ordinary converters, and that the large volume of air-blast enables me to carry on the process very rapidly. By the term "large volume of air" I mean larger than is employed in ordinary converters per unit of charge in present practice.

My invention enables me to work with a minimum of labor and to produce converted metal at a temperature suitable for casting or for delivery in molten condition into a furnace for subsequently refining. It also enables me to add silica and other fluxes to the charge instead of depending upon the converter lining to supply the silica needed for the slagging of the impurities.

By reason of the intense heat and greater fluidity of the contents of my converter the slag will contain a lower percentage of metal than do the converter slags of the present practice.

By handling the metal in small batches and by hastening the work of the converter I am enabled to lessen the long intervals of inaction of the men employed at the converter in the methods heretofore practiced. I am also enabled to do the work with a much less number of men for a given tonnage than has heretofore been possible.

Other advantages of my invention will be appreciated by those skilled in the art, and some of them may be briefly enumerated as follows: The ability to use without injury to the converter a vastly increased volume of heat; as a consequence, the ability to operate with much higher heats than now pre-

vail; the ability to use a cheaper lining made of refractory brick and the long life of the lining; the ability to open up the entire top of the converter quickly by machinery and without manual labor for repairs or for other purposes while in place; the ability to raise the matte to a high enough temperature to admit of its being transferred by gravity from one furnace to another, thus eliminating entirely the investments for lifting machinery and the heavy cost for labor; by reason of the great and controllable heat the ability to add a large proportion of silica flux, thus producing a lighter slag, and consequently a better separation of the slag from the matte than at present prevails; the ability to dispense with the present expensive method of lining converters with silica, which linings are from eighteen to twenty-four inches in thickness and are provided for the purpose of satisfying the iron; a large reduction in the item of labor, and the ability to convert copper in much less time than at present required.

I claim—

The method of converting copper, which consists in introducing into the molten matte a large volume of air, creating thereby an intense heat in the matte, abstracting a portion of such heat by a cooling medium at the beginning of the blow, while the oxidation is rapid, and supplementing the heat by a flame at the end of the blow when the oxidation fails; substantially as described.

In testimony whereof I have hereunto set my hand.

RALPH BAGGALY.
